MACHINE FOR CUTTING SHEET MATERIAL

John W. Dodd, Brookline, Mass.

Application November 19, 1929
Serial No. 408,252

6 Claims. (Cl. 164—54)

My invention relates to machines for cutting sheet material, particularly power-operated paper cutting shears, and it has for its object to provide an improved machine of this class.

It is also an object of this invention to improve the construction and operation of machines of the type shown and described in U. S. Patent No. 1,564,006 granted December 1st, 1925.

In the machine of the patent referred to the 10 knife-carrying cross-head has associated with it paper-engaging and clamping means frictionally controlled wholly by the knife-carrying cross-head so as to move toward the paper with the cross-head and engage the paper in advance of the knife of the cross-head to clamp the paper immovably in position upon the bed of the machine thereby to hold it against displacement while the knife is operating upon it.

Also, in the machine of the patent referred to, 20 the paper-clamping means moved upwardly with the knife-carrying cross-head immediately upon the start of the latter upon its upward movement with the result that sometimes the ascending knife would displace or disarrange the paper during the first part of its upward movement.

My present invention has for its main object to prevent this displacement of the paper by the upward movement of the cross-head and knife.

In a machine of this class constructed in accordance with my present invention the means for clamping the paper or other sheet material in position while it is being cut is operated to release the same after the knife has made its cutting stroke and been moved upwardly out of engagement with the paper that has been cut, and this is one of the distinguishing features of the present invention.

Other features and advantages of my invention are hereinafter pointed out.

40 In the accompanying drawings:

Figure 1 is a front elevation of a machine for cutting sheet material constructed in accordance with my invention.

Figure 2 is a section on line 2—2 of Figure 1.

45 Figure 3 is a side elevation of the machine shown in Figure 1.

Figure 4 is a section on line 4—4 of Figure 1.

Figure 5 is a section on line 5—5 of Figure 1.

50 Figure 6 is a front elevation of the clamping bar and some of the parts associated therewith.

Having reference to the drawings, 1 represents the frame of my improved machine for cutting sheet material, said frame including the usual bed, or work-rest 2, provided with an adjustable gauge 3. The bed 2 is made upon its top side

with a transverse groove occupied by a strip of wood, fibre or the like 62 co-operating with a knife blade 4 fastened to a cross-head 5 mounted in vertical ways 6 on the frame of the machine.

At its opposite ends the cross-head 5 is made with horizontal slots 7 to receive rolls 8 carried by slides 9 connected with the frame 1 with provision for vertical movement by the usual means including guide-rolls 10 and cross-bars 11 mounted on frame 1. The slides 9 also carry rolls 12 engaging the top side of the cross-head 5.

At their lower ends the slides 9 are pivotally connected with the upper ends of pitmen 13 whose opposite ends are connected with wrist pins 14 provided at the opposite ends of the main shaft 15 of the machine. This main shaft 15 is driven through the usual means controlled by a hand lever 58 which is manually operated to start said shaft in motion, the latter being automatically stopped at the completion of each revolution thereof. At their upper ends the slides 9 are connected as usual by a tie-rod 61 as shown in Fig. 1.

When the shaft 15 is rotated it acts through the pitmen 13, slides 9 and rolls 8 and 12, to first lower and then raise the cross-head, said shaft 15 being automatically stopped with the wrist pins 14 and cross-head 5 at the limit of their upward movement.

Immediately at the rear of the cross-head 5 is a clamp-bar 16 to the opposite ends of which are fastened vertically disposed bars 17 slidably mounted in ways 18' provided on the frame of the machine, Figs. 1, 4 and 6.

At their lower ends the slide-bars 17 are secured to the opposite ends of a cross-bar 18, to the under side of which is pivotally connected, at 19, the upper end of a bail-shaped member 20. The bail-shaped member 20 provides a vertical slot 21 that is occupied by the forwardly extending arms 22 and 23 of two levers 24 and 25 fulcrumed, respectively, at 26 and 27 upon the frame of the machine.

The upper lever 24, Fig. 4, has a rearwardly extending arm 28 on which is adjustably mounted a weight 29 sufficient to act through lever 24, cross-bar 18 and slide-bars 17, to lift clamp-bar 16, while the lever 25 is also provided with a rearwardly extending arm 30 on which is adjustably mounted a weight 31.

The clamp-bar 16 is yieldingly urged upwardly toward an abutment-bar 32 by the weight 29 acting through the connections described, the opposite ends of said bar 32 being also slidably

mounted in the ways 18 on the frame of the machine.

In addition to the two arms 23 and 30 the lever 25 is made with a third arm 59 provided 5 at its forward free end with a foot-piece 33, Figs. 1 and 4.

The arm 59 of lever 25 extends forwardly through a vertical slot 34 provided in an approximately upright apron or plate 35 forming part 10 of the frame of the machine and the upper end of this slot 34 serves as a stop engaged by arm 59 to limit the upward movement of the latter under the influence of the weight 31.

Normally the free end portion of the arm 23 15 of lever 25 occupies a position within the slot 21 of member 20 at the bottom end thereof and it will therefore be clear that when arm 23 is swung downwardly by foot pressure applied to arm 59, said arm 23 will act through member 20, 20 cross-bar 18 and slide-bars 17 to move the clamp-bar 16 downwardly into position on top of the stack of paper or the like that is to be cut.

Thus means is provided through which the clamp-bar can be manually raised and lowered 25 when desired, or as required during the use of the machine, but normally said clamp-bar is yieldingly held elevated in its normal position adjacent abutment-bar 32 by the weight 29 preparatory to the cutting operations of the 30 machine.

The inner side of the abutment-bar 32 is made 35 with a recess 36, Fig. 5, within which is loosely mounted a friction shoe 37, preferably made from wood, which is urged laterally against the rear side of the cross-head 5 by coiled springs 38. These two springs extend through holes 39 formed through the abutment-bar 32 to the outside of the latter where they abut against a relatively short presser-bar 43.

40 The abutment-bar 32 is made with a pair of holes through it in which are fixed the shanks of two tubular studs 40, the shank of each of said studs being of less diameter than its forwardly extending body portion so as to provide 45 a shoulder that is clamped against the abutment-bar 32 by a nut 41 on the threaded rear end of the shank.

Within each tubular stud 40 is loosely mounted 50 a pull-rod 42 whose rear end extends beyond the abutment-bar 32 and through an aperture provided in the adjacent end of the presser-bar 43, the end portion thereof being threaded to receive upon it nuts 44 against which presser-bar 43 is held by the springs 38.

55 At its forward end each pull-rod 42 extends beyond its stud 40, through an aperture provided through the adjacent end of a push-bar 45 and is provided at its outer end with a head 46 bearing against the outer side of said push-bar.

At its middle the push-bar 45 is made with a 60 threaded aperture to receive an abutment screw 47 provided at its outer end with a hand wheel 48. At its inner end this abutment screw bears against a two-part friction shoe comprising a metal holder-member 49 made with a socket within which is seated a wooden friction shoe 50. These two members are made near their 65 ends with registering apertures to loosely receive the end portions of the tubular studs 40.

The studs 40 extend through oblique slots 51 formed in the cross-head 5 and have loosely mounted upon them rolls 52 normally occupying 70 positions near the lower ends of said slots.

It will be clear that by adjustment of screw 47 the springs 38 may be compressed to the desired degree and their inner or front ends will force the friction shoe 37 against the rear side of the cross-head 5 while their opposite ends act through bar 43, pull-rods 42, push-bar 45, and screw 47 to force the friction shoe 49—50 against the opposite front face of the cross-head. Thus the abutment-bar 32 is frictionally clamped to the cross-head 5 by which it is normally supported by equal pressures exerted upon opposite sides thereof by the friction shoes that are carried by the abutment-bar 32. In this way the pressures of the shoes which frictionally clamp the abutment-bar 32 to the cross-head 5 are opposed and balanced as in the above noted patent so that there is no tendency toward distortion of the cross-head. 80 85 90

The arm 22 of lever 24 which normally occupies the upper end of slot 21 of the member 20 has pivotally connected to it one end of a link 53 which extends downwardly therefrom through an eye or hole provided at the free end of a lever 54 fulcrumed at 55 on the frame of the machine and carrying a cam-roll 56 co-operating with a cam 57 fast on the main crank shaft 15. 95 100

The lower end portion of link 53 is threaded and provided with a pair of nuts 60 to co-operate with lever 54.

When the machine is started by the usual control lever 58, Fig. 1, the main crank shaft 15 makes 105 one revolution and stops and during this revolution the wrist pins 14 of shaft 15 first lower and then raise the cross-head 5 while at the same time the cam 57 is rotated to the extent of one revolution. 110

During the downward travel of cross-head 5 the clamp-bar 16 is simultaneously lowered by cam 57 acting through lever 54, link 53 and lever-arm 22, until the said clamp-bar comes to rest upon the top of the stack of paper on the bed 2. 115 The cam 57 is shaped and timed so that during this first part of the revolution of shaft 15 the clamp-bar 16 moves by gravity downwardly under the control of said cam at a faster rate of speed than the cross-head 5. Thus after clamp-bar 16 120 comes to rest upon the stack of paper on bed 2, and until the cutting edge of knife 4 reaches said stack, the said clamp-bar is urged downwardly by gravity so as to exert a preliminary pressure upon the stack of paper that is less than the maximum 125 downward pressure later to be exerted by said clamp-bar.

Continued descent of the cross-head lowers the abutment-bar 32 into engagement with the now stationary clamp-bar 16 before the cutting edge 130 of knife 4 reaches the bottom of clamp-bar 16 so that thereafter, while the cutting edge is moving down toward the bottom of clamp-bar 16 and abutment-bar 32 is at rest on the latter, an additional, but not yet maximum, downward pressure 135 is exerted by the clamp-bar upon the paper stack because of the frictional connection between the abutment-bar 32 and cross-head 5 and the downward pressure of the upper sides of slots 51 upon rolls 52 on abutment-bar 32. 140

During this downward movement of the cross-head after abutment-bar 32 comes to rest on clamp-bar 16, said cross-head is deflected endwise toward the left, Fig. 1, so that then the movement of the cross-head is obliquely downward until it 145 reaches the limit of its downward movement. This oblique movement starts as soon as abutment-bar 32 comes to rest upon clamp-bar 16.

When, during the descent of the cross-head, the cutting edge of the knife 4 engages the stack of 150

- paper on table 2, the resistance of the paper to the descent of the knife and cross-head re-acts through the rolls 52 and abutment-bar 32 to cause the clamp-bar 16 to exert its maximum downward pressure upon the stack of paper so that the latter is securely held against displacement while the knife is forced therethrough.
- The cam 57 is timed to maintain the arm 22 depressed for about three-quarters of the revolution of shaft 15 so that during the last quarter of the revolution of said shaft the arm 22 is raised by the weight 29. Thus the cam 57 delays the start of the upward movement of clamp-bar 16 under the influence of weight 29 until after the knife blade 4 has been raised by wrist pins 14 sufficiently to carry it out of engagement with the work on the table 2. In this way I prevent the displacement of the paper or other work on table 2 by the upward movement of the blade 4.
- At the start of the upward movement of the cross-head 5 the abutment-bar 32, because of its frictional connection with said cross-head, moves upwardly with the latter, but before the cross-head reaches the limit of its upward movement a spring 58 carried by said abutment-bar comes into position against a stop 63 on the frame of the machine thereby yieldingly stopping further upward movement of the abutment bar so that thereafter the cross-head 5 continues its upward movement alone. During the period of time between the engagement of spring 58 with the stop 63 and the completion of the upward movement of cross-head 5, the slots 51 co-act with rolls 52 to return said cross-head to its position at the limit of its movement toward the right, Fig. 1.
- What I claim is:**
1. A machine for cutting sheet material comprising a knife-carrying cross-head; means including a main shaft for reciprocating said cross-head vertically with provision for movement thereof endwise also; an abutment-bar frictionally connected with said cross-head so as to be moved vertically by the latter; a vertically movable clamp-bar beneath said abutment-bar serving through its engagement with the work to stop the downward movement of said abutment-bar with the cross-head; means yieldingly supporting said clamp-bar; means through which said abutment-bar acts to deflect said cross-head endwise in one direction when the downward movement of said abutment-bar with the cross-head is arrested by the clamp-bar; a stop to limit the upward movement of said abutment-bar with said cross-head; means through which said abutment-bar acts to deflect said cross-head endwise in the opposite direction when the upward movement of said abutment-bar is arrested by said stop, and a cam on said main shaft operating at the start of the upward movement of the cross-head to maintain said clamp-bar in engagement with the work until after the knife of the cross-head has been moved upwardly out of engagement with said work.
2. A machine for cutting sheet material constructed in accordance with claim 1 wherein the said cam controls the means for yieldingly supporting said clamp-bar to maintain the latter in engagement with the work until after the knife of the cross-head has been moved upwardly out of engagement with said work. 80
3. In a machine of the character described the combination of a vertically movable clamp-bar structure; a lever having one arm thereof in abutting engagement with said clamp-bar structure; a weight constituting part of the other arm of said lever and operating through the latter to support said clamp-bar in an elevated position; a main shaft; a cam on said main shaft; a lever operated by said cam, and a link connecting said two levers through which said cam and its lever act to adjust said first-mentioned lever thereby to raise and lower said clamp-bar. 85
4. A machine of the character described constructed in accordance with claim 3 wherein manually operated means is also provided by which said clamp-bar is raised and lowered while said shaft and cam are at rest. 90
5. A machine of the character described comprising a main shaft; a vertically movable knife-carrying cross-head; means through which said shaft operates to reciprocate said cross-head; a vertically movable clamp-bar structure associated with said cross-head; a lever having one arm thereof in abutting engagement with said clamp-bar structure and another arm provided with a weight by which said lever is caused to support said clamp-bar in an elevated position; a foot-operated lever having an arm thereof co-operating with said clamp-bar structure, a cam on said shaft; means connected with said first-mentioned lever through which said cam operates the same thereby to raise and lower said clamp-bar structure independently of said foot-operated lever and in timed relation with the movements of said cross-head. 100
6. A machine of the character described comprising a movably supported knife-carrying cross-head; a work-rest; means by which said cross-head is moved toward and from said work-rest; work-clamping means associated with said cross-head and movable toward and from said work-rest; means for shifting said work-clamping means toward and against the work on said work-rest as said cross-head is moved toward said work-rest but at greater speed than that at which said cross-head is then moved; means through which said cross-head acts to hold said work-clamping means against the work while the latter is being cut, and means for moving said work-clamping means away from said work-rest after said cross-head has been moved away from the latter far enough to disengage its knife from the work. 110
